(57) **CLAIM**

The ornamental design for a hitch step, as shown and described.

DESCRIPTION

FIG. 1 is an isometric view of my design, the trailer hitch receiver post and an identification tag being shown in broken line as environmental structure;

FIG. 2 is a top plan view of my design;

FIG. 3 is a front view of my design;

FIG. 4 is a side view of my design; and,

FIG. 5 is a rear view of my design.

The broken line showing of the environment is for illustrative purposes only and forms no part of the claimed design. The bottom of the hitch step is unadorned and forms no part of the claimed design.

The hitch step is shown on a reduced scale in FIGS. 2-5.
